JAMES M. SEYMOUR, JR., OF NEWARK, NEW JERSEY.

STEAM-GENERATOR.

1,178,956.

Specification of Letters Patent. Patented Apr. 11, 1916.

Application filed March 10, 1915. Serial No. 13,300.

To all whom it may concern:

Be it known that I, JAMES M. SEYMOUR, Jr., a citizen of the United States, residing at Newark, in the county of Essex and State 5 of New Jersey, have invented certain new and useful Improvements in Steam-Generators; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention has reference, generally, to improvements in steam generators; and the invention relates, more particularly, to an efficient and economical apparatus for generating steam by the application of heat 20 to water without waste or loss of any of the thermal units liberated by combustion in accordance with the principles of the present invention.

The present invention has for its principal 25 object to provide a novel construction of steam generator or boiler provided with an internal means, preferably submerged in the water contained in the boiler, for applying heat directly to the water, thus doing away 30 with external fireboxes, burners, or the like, and also eliminating flues, chimneys, etc., in connection with said boiler. It is a well recognized fact that under ordinary boiler 35 practice whereby heat is applied externally to the boiler, a great percentage of the thermal units liberated by external combustion are lost and wasted, both on account of radiation and loss through flues and chimneys.

It is the object of my invention, therefore, 40 to so provide the location of combustion that the thermal units liberated thereby are transmitted directly and immediately to the water in the boiler, so that the water takes up all the heat generated by the combustion, 45 therefore producing for a given amount of fuel a far greater amount of steam than could be produced by any form of external heated or flue boiler.

Other objects of the present invention, not 50 at this time more particularly enumerated, will be clearly understood from the following detailed description of the same.

With the various objects of the present invention in view, the same consists, primarily, in the novel construction of the steam generator or boiler hereinafter set

forth; and, furthermore, the invention consists in the several novel arrangements and combinations of the various parts of the same, as well as in the details of the construction of said parts, all of which will be more fully described in the following specification, and then finally embodied in the claims which are appended to and which form an essential part of said specification.

The invention is clearly illustrated in the accompanying drawing, in which I have illustrated a boiler embodying one form of construction embodying the principles of my present invention, said boiler being shown in longitudinal vertical section, and certain mechanisms associated with said boiler being shown in diagrammatic style merely to illustrate one possible manner of supplying and igniting fuel in connection with my novel boiler.

Referring now to the said drawing, the reference character 1 indicates a boiler-shell of desirable form, and preferably constructed of steel. Said boiler-shell 1 is provided with a suitable water inlet pipe 2, through which water may be fed to the interior of said boiler-shell by any suitable feeding means, such as an injector, pump or the like. Located within the interior of said boiler-shell, and preferably adjacent to its lower end, so that the same is submerged in the water contained in said boiler-shell, is a retort or cylinder 3 providing a combustion-chamber 4 open at its bottom end. While it is preferable to submerge said retort or cylinder 3, I do not wish to be confined to locating the same in such position since said retort or cylinder may also perform its functions if placed above or at the water line or level of the boiler-shell. Connected with said retort or cylinder 3, and communicating with its combustion chamber 4, is a fuel conducting feed-pipe 5, the same passing from said retort or cylinder 3 outwardly through a stuffing-box 6 formed in connection with the wall of said boiler-shell 1. When desired the open end of said combustion chamber 4 may be normally closed by a spring pressed valve-member 7, although if it is desired such valve-member may be eliminated as it is not absolutely essential to the proper operation of the retort or cylinder function, as will presently be more fully understood.

The fuel to be introduced into and burned in said combustion chamber 4 of said retort

or cylinder 3 is preferably a suitable combustible gas, such as producer gas, or vapor gases from petroleum bases, or any other free burning gas, and such combustible gas is mixed with air to supply the requisite amount of oxygen to support its entire combustion, the proportion preferable of air to gas being eight volumes to one, although this proportion will be variable according to 10 the kind of gas employed.

The reference character 8 indicates a suitable pressure-tank which is supplied by air and gas compressing pumps 9 and 10 with the combustible fuel mixture. The fuel mixture 15 is therefore stored in said pressure-tank 8 under a pressure in excess of the pressure of the water in the boiler-shell 1.

Connected with the outer end of said fuel conducting feed-pipe 5 is the outlet 11 of a 20 measuring feed-valve casing 12, the inlet end 13 of which is connected by suitable fuel-conveying pipe 14 with the pressure-tank 8. The said measuring feed-valve may be made in various forms, but in the drawing 25 I have illustrated same in a rotating form, the casing 12 being cylindrical in form and containing a rotating valve-member 15 providing a measuring chamber 16. The wall of said valve-member 15 is provided with a 30 port 17 which, upon rotation of the valve-member, is registered alternately with the inlet end 13 and outlet end 11 of the valve-casing 12, and consequently carrying the measuring chamber 16 alternately in communication with the pressure-tank 8 in its 35 supply of fuel and with the combustion chamber 4 of the retort or cylinder 3. Since the fuel mixture in said pressure-tank 8 is maintained under a pressure greater than 40 the pressure of the water in the boiler-shell 1, it follows that, when the port 17 of the valve-member 15 registers in communication with the pressure-tank 8, a charge of fuel-mixture will rush into and fill said measuring 45 chamber 16. The continued rotation of the valve-member 15 will then bring the port 17 in communication with the feed-pipe 5, so that the charge of compressed fuel-mixture in said measuring chamber 16 will be 50 liberated therefrom and will thereupon pass into said combustion chamber 4 of said retort or cylinder 3. Such expansion of the fuel charge as results from its passage into the combustion chamber 4 is not sufficient to 55 reduce water in the boiler-shell 1, and consequently even though the valve-member 7 closing the open end of said retort or cylinder 3 be eliminated the water is maintained against entrance to said combustion chamber 60 4 since the pressure of the fuel therein overbalances the pressure of the water. After the fuel charge has thus been introduced into the combustion chamber 4, this combustion may take place with explosive effect which 65 expels the liberated thermal units directly

into the water, the valve-member 7, when the same is employed, being lifted from its seat by the force of the outflow of suddenly ignited or exploded fuel, so that the burning and hot gases are liberated directly into the 70 water, and the thermal units thereof are quickly taken up by the water which becomes heated to the boiling point, under the repeated operation of combustion in the retort or cylinder 3, so that steam is thus produced 75 in the upper free spaces of the boiler-shell, which may be drawn off for desired purposes through the steam outlet pipe and valve 18.

The means of accomplishing the timed ignition of the fuel charges introduced into the combustion chamber 4 of the retort or cylinder 3, comprises, preferably, an electric sparking system, having sparking terminals 19 connected with said retort or cylinder 3, the spark-gap formed thereby being located within said combustion chamber 4 and electrically connected in the circuit 20 of a battery 21, or other suitable source of electricity. Connected in said circuit 20 is the usual spark-coil 22, and also connected in said circuit 20 is a timer or make and break device 23, which is operated in synchronous timed relation to said measuring feed valve so that an ignition spark is produced after 90 the introduction of each charge of fuel with the combustion chamber 4 of the retort or cylinder 3. It will be understood that the speed of the successive introduction, ignition and combustion of the fuel in the combustion chamber 4 of the retort or cylinder 3 will be determined by the speed of the rotating measuring feed-valve, and that the frequency of combustion of fuel charges determines the amount of liberated thermal units applied to the water in the boiler-shell 1 in a given time, which frequency may be variable according to the demands upon the boiler for steam.

As a precautionary measure the fuel-conveying pipe 14 leading from the pressure-tank 8 may be provided with a back-fire or back-flash arrester 24, containing a fine mesh screen, so that any back-flash or fire from the combustion in said combustion chamber 4, even though it should perchance pass through said measuring feed-valve, cannot reach the contents of said pressure-tank 8. Of course it will be understood that the products of combustion are forced directly into the water, and comprise both hot gases and solids, the gas will rise through the water until it emerges therefrom and mixes with steam above the water, whereas the solids, such as carbon, are separated from the gases and are held in suspension in the water or precipitated to the bottom of the boiler-shell. When desired one or more screens 25 may be employed which will further tend to retard the upward flow of the 100 105 110 115 120 125 130

gas until all the thermal units it bears are absorbed by the water, and which, furthermore, will tend to hold back solids and finally assure the precipitation of the same to the bottom of the boiler-shell 1. The said boiler-shell 1 may be provided with one or more man-holes 26, of any usual construction, through which access to the interior of the boiler-shell 1 may be attained for the purposes of cleaning out the same and the retort or cylinder 3, or for replacing the spark terminals, or for any other necessary purpose, said man-holes being normally sealed by the man-hole plates 27.

15. It must be understood that my invention includes the use of one or more retorts or cylinders 3 within a boiler-shell 1, and in fact the scope of the invention is comprised in an apparatus for liberating thermal units 20 directly in contact with the water in a boiler-shell in its broadest aspect, with the result of utilizing all the thermal units produced by the fuel combustion without loss or waste. It will therefore be apparent that 25 many changes may be made in the details and arrangements of the structures shown in the accompanying drawings and described in the foregoing specification, and as defined in the appended claims, without departing from the scope of the present invention. Hence, I do not limit my invention to the exact arrangements and combinations 30 of the various devices and parts as herein set forth, and as illustrated in the accompanying drawings, nor do I confine myself 35 to the exact details of the construction of the said parts.

I claim:

40. 1. A steam generator comprising a boiler-shell, a retort within said boiler-shell providing a combustion chamber open to communication with the water in said boiler-

shell, a fuel feed-pipe communicating with said combustion chamber, a measuring valve, connected with said fuel feed-pipe adapted to liberate gas charges into said combustion chamber under compression equal to or greater than the pressure of water in said boiler-shell, a gas supply pressure-tank connected with said measuring valve, means 50 for feeding to and compressing gas and air within said pressure-tank, and means for igniting the gas charges within said combustion chamber.

2. A steam generator comprising a boiler-shell, a retort within said boiler-shell providing a combustion chamber open to communication with the water in said boiler-shell, a fuel feed-pipe communicating with said combustion chamber, a measuring valve connected with said fuel feed-pipe adapted to liberate gas charges into said combustion chamber under compression equal to or greater than the pressure of water in said boiler-shell, a gas supply pressure-tank connected with said measuring valve, means for feeding to and compressing gas and air within said pressure-tank, and means for igniting the gas charges within said combustion chamber, comprising spark-terminals within said combustion chamber, an electric circuit connecting said spark-terminals, and a timed circuit closing device for making and breaking said electric circuit to produce ignition sparks at said spark-terminals.

In testimony that I claim the invention set forth above I have hereunto set my hand this 8th day of March, 1915.
